UNITED STATES PATENT OFFICE

140,427

DESIGN FOR A SOUND HEAD FOR MOTION PICTURE PROJECTORS

Otto R. Nemeth, Chicago, Ill., assignor to Products
Development, Inc., Chicago, Ill., a corporation
of Illinois

Application December 23, 1944, Serial No. 117,050

Term of patent 14 years

(Cl. D61—1)

To all whom it may concern:

Be it known that I, Otto R. Nemeth, a National of Czechoslovakia, residing at Chicago, in the county of Cook and State of Illinois, have invented a new, original, and ornamental Design for a Sound Head for Motion Picture Projectors, of which the following is a specification, reference being had to the accompanying drawings, forming part thereof.

Figure 1 is an elevational view of a sound head for motion picture projectors embodying my new design.

Fig. 2 is a rear end elevational view of the sound head.

Fig. 3 is a top plan view of the sound head.

Fig. 4 is a front end elevational view of the sound head.

The essential features of the design reside in the parts shown in full lines.

I claim:

The ornamental design for a sound head for motion picture projectors, substantially as shown and described.

OTTO R. NEMETH.
